(57) **CLAIM**

The ornamental design for an activity and physiological monitoring apparatus worn on the limb, as shown and described.

DESCRIPTION

FIG. 1 is a side perspective view of an activity and physiological monitoring apparatus worn on the limb showing my new design;

FIG. 2 is a rear perspective view thereof;

FIG. 3 is a top view thereof;

FIG. 4 is a front perspective view thereof;

FIG. 5 is a top perspective view thereof;

FIG. 6 is a rear view thereof; and,

FIG. 7 is a bottom perspective view thereof.
